(57) **CLAIM**

The ornamental design for a food product, as shown and described.

DESCRIPTION

FIG. 1 is a front right perspective view of a first embodiment of a food product showing our new design;

FIG. 2 is a front elevation view of the first embodiment of the food product shown in FIG. 1;

FIG. 3 is a rear elevation view of the first embodiment of the food product shown in FIG. 1;

FIG. 4 is a right side elevation view of the first embodiment of the food product shown in FIG. 1;

FIG. 5 is a left side elevation view of the first embodiment of the food product shown in FIG. 1;

FIG. 6 is a top plan view of the first embodiment of the food product shown in FIG. 1;

FIG. 7 is a bottom plan view of the first embodiment of the food product shown in FIG. 1;

FIG. 8 is a front right perspective view of a second embodiment of a food product showing our new design;

FIG. 9 is a front elevation view of the second embodiment of the food product shown in FIG. 8;

FIG. 10 is a rear elevation view of the second embodiment of the food product shown in FIG. 8;

FIG. 11 is a right side elevation view of the second embodiment of the food product shown in FIG. 8;

FIG. 12 is a left side elevation view of the second embodiment of the food product shown in FIG. 8;

FIG. 13 is a top plan view of the second embodiment of the food product shown in FIG. 8; and,

FIG. 14 is a bottom plan view of the second embodiment of the food product shown in FIG. 8.

The broken lines shown in FIGS. 1-14 illustrate portions of the food product that form no part of the claimed design. The break lines shown in the middle portion of the food product in FIGS. 1, 4-7 indicate that the appearance of any portion of the article between the break lines forms no part of the claimed design.

1 Claim, 4 Drawing Sheets
